J. S. THOMPSON

MOLD FOR MAKING CASTINGS

Filed Dec. 28, 1923

19 Inventor:
18 James S. Thompson
184: 77 W. 9th St. Atty.

UNITED STATES PATENT OFFICE.

JAMES S. THOMPSON, OF PELHAM, NEW YORK.

MOLD FOR MAKING CASTINGS.

Application filed December 28, 1923. Serial No. 688,162.

To all whom it may concern:

Be it known that I, JAMES S. THOMPSON, a citizen of the United States, residing at Pelham, in the county of Westchester and 5 State of New York, have invented certain new and useful Improvements in Molds for Making Castings, of which the following is a specification.

This invention relates to permanent 10 molds for making castings, and its object is generally to facilitate opening the mold after the metal has been poured, and to enable this operation to be quickly and easily accomplished.

15 In making castings in permanent molds, the cope sometimes sticks to the drag and the casting and more or less difficulty is experienced in opening the mold. This may also happen when the casting is provided 20 with projections which may be located where they will add to the difficulty of opening the mold.

I have found in practice that if one end of the cope is "kicked" up slightly, it will be 25 sufficient to break that "sticking" which sometimes occurs to a degree which makes it difficult to open the mold, and since it is desirable that the mold should open easily when the time comes for opening it, with the 30 least amount of exertion and without interrupting or delaying the progress of the workman who is opening a floor of molds, it is the object of my invention to provide each mold with means whereby the cope will be 35 given a kick or jar to release it from sticking contact with the drag and casting preliminary to the opening operation.

And a further object of the invention is to provide means to facilitate opening the 40 mold which will impart this "kick" to the cope preliminary to the opening operation.

In the accompanying drawings I have 45 illustrated the invention in a simple form of mold adapted for casting brake shoes, and referring thereto,—

Fig. 1 is a side elevation showing the mold in full lines in molding position and in broken lines with the cope kicked up slightly with reference to the drag.

50 Fig. 2 shows the mold in open position.

Fig. 3 is a top plan view of the mold shown in Fig. 1.

Referring to the drawings the mold comprises a drag 5, and a cope 6 having a mold 55 cavity 7. The drag and cope are provided, at one end, with projections 8 and 9 to form

the pouring gate 10, and the cope has an end 11 to engage the other end 12 of the drag. In Fig. 2 I have shown a brake shoe casting in the drag and as is well known, such a casting has an attaching lug 13 and end lugs 13' which project from the back of the shoe and, in the form of mold illustrated, are formed in that part of the mold cavity which is located in the cope, as shown in broken lines in Fig. 65 1. There is a normal tendency of the cope to stick to the drag of a permanent mold, and especially when they are made principally of metal, after the metal has been poured to form the casting, and the provision of projections on the casting extending 70 into the cope often tends to increase this sticking as hereinbefore indicated. It is desirable to swing the cope in an arc as a simple and convenient method of opening the 75 mold and it will be readily understood that the labor of doing this will be increased if the cope sticks to the drag and casting. Therefore, I provide a pair of kicking levers 14 which are pivoted between their ends 80 at 14' on the sides of the drag and project beneath lugs 15 at the end of the cope opposite the pouring gate. The free ends of these levers, the right ends shown in the drawing, are adapted to be depressed in a 85 suitable manner to raise the opposite ends of the levers and loosen or dislodge or lift the cope free from the drag and casting as indicated in broken lines in Fig. 1, after which, it will be readily seen, the cope can 90 be easily swung to open position as shown in Fig. 2. The kicking levers, which are so named because they impart a kick to the cope, may be operated by standing on them 95 and exerting pressure through the weight of the workman, but I prefer to provide mechanical means for this purpose, and I combine the kicking lever operating means with the handle for swinging the cope to open position. This operating means comprises the handle 16 pivoted at 17 to the cope and provided with cams 18 to engage the kicking levers. The projections 19 on the cope limit the movement of the cam lever so that it will normally stand in substantially upright position, as shown in Fig. 100 1, and when the cope is open, as shown in Fig. 2, the lever may be permitted to engage a rest or support 20 to hold the cope in open position.

105 Thus the handle is employed to operate the kicking levers and to swing the cope

to open position, and the construction is preferably such that these two operations are practically simultaneous, although the kick will precede any appreciable swinging 5 movement of the cope.

My invention provides a simple and easily operated means for loosening the cope to facilitate the removal of the cope from the drag, after the metal has been poured in 10 the mold, and it will entirely overcome any sticking of the cope to the drag and casting due to the pouring operation. The broken lines in Fig. 1 show very clearly how the kicking levers operate to loosen 15 the cope from the drag. It is not necessary that the cope should be lifted as much as shown by the broken lines in Fig. 1; on the other hand the conditions may be such that it becomes desirable to lift the cope 20 as much, if not more, as shown by the broken lines in Fig. 1. My invention is adapted to accomplish these desirable results and it can be changed as found expedient to impart a desired loosening movement to the cope which, as before indicated, 25 may vary in extent for different castings or because of other conditions. The invention greatly facilitates the operation of opening the mold which can be accomplished 30 by a straight pull upon the lever; and as indicated in Fig. 2, the lever may be engaged with any sort of a support to maintain the cope in substantially upright position between casting operations.

35 I am aware that changes in the form, proportion and arrangement of parts may be made to adapt my invention to molds of different sizes, shapes and kinds for making different kinds of brake shoes or other 40 castings, and I consider myself entitled to make all such changes as fairly fall within the spirit and scope of the invention.

I claim:

1. A permanent mold for making castings comprising a drag and a cope, a projection on the cope, and a lever on the drag adapted to be operated to engage the projection of the cope for loosening the cope from the drag and casting after the casting has been made.
2. A permanent mold for making castings comprising a drag and a cope, projections on the sides of the cope adjacent one end

thereof, and levers pivotally mounted on the sides of the drag and adapted to be operated to engage the projections on the cope for 55 loosening the cope from the drag and casting after the casting has been made.

3. A permanent mold for making castings comprising a drag and a cope, a projection on the cope, a lever on the drag adapted to 60 be operated to engage the projection on the cope for loosening the cope from the drag and casting after the casting has been made, and means on the cope for operating the lever on the drag.

4. A permanent mold for making castings comprising a drag and a cope, a projection on the cope, a lever on the drag adapted to be operated to engage the projection on the 70 cope for loosening the cope from the drag and casting after the casting has been made, and a cam lever pivotally mounted on the cope for engaging and operating the lever on the drag.

5. A permanent mold for making castings comprising a drag and a cope, a projection on the cope, a lever pivotally mounted between its ends on the drag and having one end arranged to engage the projection on the 75 cope, a cam pivotally mounted on the cope to engage the other end of the lever, and a handle for operating said cam.

6. A permanent mold for making castings comprising a drag and a cope, a projection on the cope at one end thereof, a lever pivotally mounted between its ends on one side of the drag and having one end arranged beneath the projection on the 80 cope, a cam pivotally mounted on the cope to engage the other end of the lever, and a handle connected with said cam for operating the cam.

7. A permanent mold for making castings comprising a drag and a cope, projections on the cope at one end thereof, levers pivotally mounted on the sides of the drag and having one end thereof arranged to engage the projections on the cope, cams pivotally mounted on the cope to engage the other ends of the levers, and handles 95 projecting upward from the cope and engaged with said cams for operating the 100 cams.

JAMES S. THOMPSON.
